UNITED STATES PATENT OFFICE.

LEWIS C. BAYLES, OF JOHANNESBURG, TRANSVAAL, ASSIGNOR TO INGERSOLL-RAND COMPANY, OF NEW YORK, N. Y., A CORPORATION OF NEW JERSEY.

VALVE-MOTION FOR ROCK-DRILLS.

1,077,584.

Specification of Letters Patent.

Patented Nov. 4, 1913.

Application filed October 28, 1909. Serial No. 525,002.

To all whom it may concern:

Be it known that I, LEWIS C. BAYLES, a citizen of the United States, and resident of Johannesburg, Transvaal, have invented a new and useful Valve-Motion for Rock-Drills, of which the following is a specification.

This invention relates to a valve motion for rock drills and has for its object to provide certain improvements in the construction, form and operation of the valve mechanism whereby a valve may be employed which is very simple in construction, positive in its action and which has a very slight movement to accomplish the alternate opening and closing of the inlet and discharge passages for the opposite ends of the piston chamber, the action of the valve being automatic.

20 A practical embodiment of my invention is represented in the accompanying drawings, in which—

Figure 1 represents in longitudinal central section so much of a rock drill as will give a clear understanding of my invention, Fig. 2 is a section taken in the plane of the line A—A of Fig. 1, looking in the direction of the arrows, Fig. 3 is a top plan view of the cylinder, the valve chest being shown 30 in horizontal section taken in the plane of the line B—B of Fig. 1, and Fig. 4 is a detail view similar to Fig. 3, with the valve in its position opposite to that shown in Fig. 3.

35 The cylinder of the rock drill is denoted by 1 and its piston by 2. The valve chest is denoted by 3, which valve chest is provided with a motive fluid inlet chamber 4 and outlet chamber 5. Intermediate the 40 chambers 4 and 5 is located a vertical cylindrical chamber 6 from which diametrically opposite slots 7, 8, lead to the chambers 4 and 5, respectively.

A winged valve 9, 10, 11, has its cylindrical body portion 9 fitted to the cylindrical chamber 6, its wing 10 projected into the slot 7 and its wing 11 projected into the slot 8. The width of the slots 7 and 8 and the thickness of the wings 10 and 11 are 50 such that the valve is permitted a slight oscillatory movement for bringing the opposite faces of the wing 10 alternately into engagement with valve seats 12, 13, and the opposite faces of the wing 11 alternately 55 into engagement with valve seats 14, 15.

Ports 16, 17, lead from the valve seats 12, 13, to motive fluid inlet passages 18, 19, which open into the back and front ends respectively of the cylinder 1. Ports 20, 21, lead from the valve seats 14, 15, to discharge 60 passages 22, 23, which open, respectively, into the back and front ends of the cylinder 1 intermediate the port openings of the motive fluid inlet passages 18, 19.

Presupposing the parts to be in the position shown in Figs. 1, 2 and 3, with the piston 2 traveling in the direction shown by the arrow thereon, the wing 10 of the valve has opened the motive fluid inlet passage 18 to the main inlet chamber 4 and has closed the motive fluid inlet passage 19. At the same time, the wing 11 of the valve has opened the discharge passage 23 to the common outlet chamber 5 and has closed the discharge passage 22. As the piston 2 nears 70 the limit of its forward movement, it will first close the discharge passage 23 and for the balance of its forward movement will compress the motive fluid in the passage 19 sufficiently to throw the valve over into the 75 position shown in Fig. 4, thus opening the motive fluid inlet passage 19 to the main inlet chamber 4 and opening the fluid discharge passage 22 to the main outlet chamber 5, and at the same time, closing the inlet passage 18 and the outlet passage 23. This will start the piston on its return movement and as it nears the limit of its return movement it will first close the discharge 80 passage 22 and then compress the fluid sufficiently in the inlet passage 18 to throw the valve back to the position shown in Fig. 3.

It will thus be seen that the valve and ports, constructed and arranged as herein set forth, permits the valve to control the 95 opening and closing, not only of the inlet passages but also of the discharge passages so as to insure a sufficient overbalancing of pressure upon the valve wings to throw the valve automatically at the desired times to 100 insure the proper reciprocation of the piston.

While I have shown this valve mechanism in connection with a rock drill, it is to be understood that I do not wish to limit myself to such use but contemplate its use 105 wherever applicable in percussive machines or tools.

What I claim is:

1. A cylinder having independent inlet and discharge passages for both ends, its 110

10 piston, a valve chest and a fluid actuated double winged oscillating valve having one wing arranged to control the inlet passages and the other wing arranged to control the discharge passages.

15 2. A cylinder having independent inlet and discharge passages for both ends, its piston, a valve chest and a fluid actuated double winged oscillating valve having one wing arranged to alternately open and close the inlet passages and the other wing arranged to alternately open and close the discharge passages.

20 3. A cylinder, its piston, a valve chest having independent inlet and discharge passages for both ends of the cylinder, and a fluid actuated double winged oscillating valve having one wing arranged to open the inlet passage for one end of the cylinder at the same time that its other wing opens the discharge passage for the other end of the cylinder.

25 4. A cylinder, its piston, a valve chest having independent inlet and discharge passages for both ends of the cylinder and a fluid actuated double winged oscillating valve having one wing arranged to open the inlet passage for one end of the cylinder at the same time that its other wing opens the discharge passage for the other end of the cylinder, said first named wing also being arranged to close the other inlet passage at the same time that the second named wing closes the other discharge passage.

30 5. A cylinder, its piston, a valve chest having inlet and discharge passages for both ends of the cylinder and a double winged oscillating valve having one wing arranged

35 to alternately open and close the inlet passages and another wing arranged to alternately open and close the discharge passages.

40 6. A cylinder, its piston, a valve chest having main motive fluid inlet and outlet chambers, a valve chamber, diametrically oppositely arranged slots leading therefrom to the inlet and outlet chambers, inlet passages for both ends of the cylinder having ports leading from the slot communicating with the inlet chamber, discharge passages for both ends of the cylinder having ports leading from the slot communicating with the outlet chamber and a double winged oscillating valve seated in the valve chamber with its wings located in said slots for alternately opening and closing the inlet and discharge passages.

45 7. A cylinder, its piston, a valve chest containing a valve chamber having two radially disposed slots one communicating with the motive fluid inlet and the other with external atmosphere, inlet passages for both ends of the cylinder leading to the inlet slot, discharge passages for both ends of the cylinder leading to the exhaust slot and a double winged oscillating valve seated in the valve chamber with its wings located in said slots for alternately opening and closing the inlet and discharge passages.

50 In testimony, that I claim the foregoing as my invention, I have signed my name in presence of two witnesses, this twenty-seventh day of October 1909.

LEWIS C. BAYLES.
